HAMMER MECHANISM FOR FIREARMS
Charles Edward Rowe, Jr., Templeton, Mass. (9% Harrington & Richardson, Inc., Park Ave., Worcester, Mass. 01605)

Filed Aug. 24, 1966, Ser. No. 574,742
4 Claims. (Cl. 42—20)

ABSTRACT OF THE DISCLOSURE

A firearm having a hammer and a sear therefor, and a reciprocating power-operated bolt which causes the hammer to be retracted to a position where it is caught by the sear and both the hammer and sear having independent springs and inter-engaging impact means on the hammer and sear limiting the motion of the hammer under influence of the bolt so that it will not rebound under actuation by the bolt.

This invention relates to a new and improved hammer mechanism for firearms, the principal object of the invention residing in the provision of means associated with a hammer for a firearm particularly of the semi- or automatic type whereby the hammer is protected against damaging other parts of the mechanism upon the power operated action of the bolt. It has been found that in some firearms the force of the motion of the bolt is so extreme as to strike the hammer unduly and cause it to rebound with considerable force against other parts of the firearm including the sear and parts of the receiver and pins, etc. adjacent the sear.

The invention in the present case however provides means whereby the hammer rebounds with respect to this sear and takes advantage of the position of the sear spring in such a way as to dampen this excessive effect, thus improving the action.

Other objects and advantages of the invention will appear hereinafter.

Reference is to be had to the accompanying drawings in which:

FIG. 1 is a sectional view through a firearm receiver showing the firing mechanism with the hammer in cocked position;

FIG. 2 is a similar view showing the hammer in firing position;

FIG. 3 is a view illustrating the hammer and the sear in the extreme retracted position of the hammer, and

FIG. 4 shows a modification.

Referring now to FIG. 1 there is shown a firearm which has a receiver 10, a barrel 12, a reciprocating bolt 14, an action rod 16, and various other necessary but conventional parts.

There is a firing pin 18 in the bolt and it will be seen that the bolt is of the delayed blow-back action type which carries with it the action rod 16, the action rod also recocking the firing mechanism.

The hammer is shown as pivoted on a pin 20, the hammer being indicated at 22 and having a spring 24 tending to move the hammer in a counterclockwise direction in order to strike the firing pin 18 when the trigger at 26 is pressed. The trigger has interengagement

2

with the sear which is indicated at 28 as explained in copending patent application Ser. No. 415,307 filed Dec. 2, 1964, now U.S. Patent 3,314,183, and it is pivoted in the receiver on the sear pin 30. As shown considerably to the right of the pin 30 in FIG. 1, there is a sear spring 32 which tends to move the sear to the hammer-locking condition shown in FIG. 1, spring 32 bearing against a point on the bottom of the receiver which is indicated at 34.

10 The hammer and sear have interengaging nose portions at 36 by which the hammer is cocked as shown in FIG. 1, and these portions are provided also with adjacent cam areas etc. at 38 and 40 to provide for the nose 36 on the hammer to slip past the corresponding nose on the sear so as to achieve the cocking effect.

15 In this case the hammer has a novel feature provided in an extending barrier member 42 which extends upwardly to the rear and as shown in FIG. 1 overlies the sear. When the bolt is moved toward the rear with great energy, the extending portion or barrier 42 strikes the top of the sear on the surface thereof which is indicated at 44 causing the sear to move slightly in a counterclockwise direction against the action of the sear spring 32. The barrier 42 prevents the hammer from moving any 20 farther in a clockwise direction than is indicated in FIG. 3 and thus saves the bottom of the receiver and the area of the sear adjacent the sear pin 30 from a battering effect which would otherwise be present. The sear spring acts as a dashpot cushioning the entire effect and at the same 25 time is sufficient to bring the sear back into hammer-nose engaging position as shown at 36 in order to cock the firearm. Also of course as shown in FIG. 2, when the trigger is pressed the sear is moved in a clockwise direction to release the nose engagement at 36 and allow the hammer spring 24 to move the hammer to firing position, see FIG. 2.

30 The relative angles of the striking faces of the barrier 42 and the sear can be altered according to the effect to be produced. Thus if these surfaces are largely diametrical relative to the center of trigger pin 20, the blow on sear surface 44 is relatively great. However if these surfaces are changed to tangential to larger and larger circles about pin 20, the degree of blow is lessened and a kind of wiping action appears between the surfaces 35 of the barrier and sear, rather than a sharp hammer-like blow. This is illustrated at 46 in FIG. 4.

35 Having thus described my invention and the advantages thereof, I do not wish to be limited to the details herein disclosed, otherwise than as set forth in the claims, but what I claim is:

40 1. In a firearm of the type having a hammer and a sear therefor, and a reciprocating power-operated bolt which causes the hammer to be retracted to a position where it is caught by the sear and both the hammer and sear having independent springs, that improvement which includes interengaging impact means on the hammer and sear limiting the motion of the hammer under influence of said bolt, said interengaging means including a projection on the hammer.

45 2. The firearm of claim 1 wherein said projection on the hammer is located in a position to strike the sear and the sear spring is in a position to aid in absorbing the impact.

3. The firearm of claim 1 wherein the hammer and sear are independently pivoted on parallel axes with interengaging cocking means between them for holding the hammer cocked, the sear spring being located to one side of the axis of the sear, the projection on the hammer overlying the sear in cocked condition of the hammer.

4. The firearm of claim 1 wherein the hammer and sear are independently pivoted on parallel axes with interengaging cocking means between them for holding the hammer cocked, the sear spring being located to one side of the axis of the sear and the interengaging impact means between the hammer and the sear being in the form of a projection of the hammer overlying the sear

5 4
in cocked condition of the hammer in a position to strike the sear and compress the sear spring, the latter acting as a resilient takeup for the blow of the hammer projection on the sear.
